United States Patent Office.

ERASTUS W. SCOTT, OF WAUREGAN, CONNECTICUT.

Letters Patent No. 96,149, dated October 26, 1869; antedated October 16, 1869.

IMPROVED SHUTTER-WORKER.

The Schedule referred to in these Letters Patent and making part of the same.

all persons to whom these presents may come:

Be it known that I, ERASTUS W. SCOTT, of Wau-
regan, in the county of Windham, and State of Con-
necticut, have invented a new and useful Mechanism
for Operating a Window-Blind; and do hereby de-
clare the same to be fully described in the following
specification, and represented in the accompanying
drawings, of which—

Figure 1 is a front elevation of a window-frame
and a blind provided with my invention.

Figure 2 is a vertical and transverse section, taken
through the operative spindle.

Figure 3 is a horizontal section, taken through the
lower part of the blind.

The mechanism is to effect the opening and closing
of the blind, as well as the opening and closing of its
series of slats.

In the drawings—

A denotes the window-frame, and B the blind, the
latter being hinged to the former, as shown at *a a*.

The lower hinge of the blind is provided with a
bracket or arm, *b*, which projects from the window-
frame, and directly over and on the upper end of the
hinge, in order to keep the blind from rising while
being put in motion.

There extends transversely through the window-
frame a spindle, C, which is encompassed by a tube
or sleeve, D, having a knob, E, fixed to its inner end.

The sleeve slides freely on the spindle, and is kept
in connection therewith by a stud, *c*, which projects
from the spindle into a slot, *d*, formed lengthwise on
the sleeve.

At its outer end the slot is turned at a right angle,
or has a notch, *e*, leading from it, in manner as shown
in Figure 4, which is a top view of the sleeve D and
the spindle C.

By turning the sleeve so as to bring the stud into
the notch, and by forcing endwise on the tube or
sleeve, or by pulling it back, an endwise motion may
be imparted to the spindle.

The spindle may also be revolved by revolving the
tube.

The tube or sleeve, so combined with the knob
and the spindle, is to enable the knob to be moved
forward underneath the window-seat *f*, so as to be
out of the way when not in use.

The spindle, at its outer end, has an arm, *g*, pro-
jecting from it at a right angle to it.

The said arm extends through a slot, *h*, made in a
metallic plate, *i*, fastened to the blind, and arranged
therewith in manner as represented.

The arm goes between two arms *k l*, one of which
extends from a latch, *F*, and the other from the im-
pelling-pawl *G* of a ratchet, *H*.

The latch *F* is to operate with two catches *I K*,

one of which projects from the window-frame, and
the other from the side of the building containing
the window-frame.

The latch goes through a projection, *m*, extending
from the plate *i*.

Such latch also goes through an arm, *n*, extended
from the pawl *G*.

A helical spring, *o*, enveloping the latch, and resting
at one end against the projection *n*, and at the
other against an arm, *p*, which extends up from the
latch in manner as represented, serves to advance the
latch, and to retract the pawl, as occasion may re-
quire.

Another spring, *q*, attached at its lower end to the
pawl, and at its upper end to the upper part of the
arm *p*, is to draw the pawl up to the periphery of the
ratchet.

Furthermore, the latch, near its front end, goes
through a guide, *r*, extended from the blind.

The ratchet *H*, placed against the middle of the
lower bar of the blind-frame, is held thereto by a
screw, *S*, such ratchet being free to revolve thereon.

The ratchet is connected with the operative bar *t*
of the series of slats *u u u*, &c., of the blind, by
means of a connection-rod, *v*, which is pivoted to the
said bar at its lower end, and to a crank-pin, *w*, ex-
tended from the ratchet.

Figure 5 represents a transverse section of the
blind, showing the bar *t*, and its connections with the
slats, each of such connections consisting of two
staples, *x y*, one of which is hooked into the other. One
of them is driven into the bar, and the other into the
slat.

If, now, we suppose the blind open, and we desire
to close it, we first lay hold of the knob, and draw it
and the sleeve back on the spindle. Next we turn
the knob, so as to cause the arm of the spindle to
retract the latch, in a manner to unlatch the blind
with the back catch. Next we press the spindle for-
ward, so as to move the blind rather more than ninety
degrees on its hinges, after which the spindle is to be
drawn backward, so as to cause the blind to close
and the latch to engage with the inner catch.

We can effect the disengagement of the latch from
the inner catch, and the subsequent opening move-
ments of the blind, in a similar way by the knob and
spindle.

By means of the said knob and spindle, we can
also so move the pawl as to turn the ratchet more or
less, in order to effect the closing or the opening of
the blind-slats.

From the above, it will be seen that we not only
have a means of operating the blind from within the
building or apartment thereof containing the window,
but also have a means by which a person, while in

such apartment, can also, by his hand applied to the knob, effect the opening or closing of the slats of the blind.

I claim the combination and arrangement of the sleeve D, slotted and recessed, as described, with the knob E, the spindle C, the stud e, the arm g, the slotted plate i, and the spring-latch F, to operate with catches I K, applied to the window-frame A and the building, as explained.

I also claim the arrangement of the latch F, the

pawl G, the arms n p, and the two springs o q, applied to the said arms, latch, and pawl, as set forth.

I also claim the combination of the spindle C, its arm g, and the slotted plate i, with the pawl G, the spring q, ratchet H, arm v, and bar t, the whole being applied to the blind and the window-frame, substantially in manner and for the purposes as set forth.
